To all whom it may concern:

Be it known that we, LUCETTA BRADFIELD and ROSELMA C. The leading feature of our design consists of an ornamental wire, semi-circular in form and provided with ornamental loops or curves and bent to form ornamental twisted arms and a straight transverse arm.

Referring to the said drawing, the reference numeral 1 designates a semi-circular wire 20 formed with a number of ornamental loops or curves 2, the bent and twisted ornamental arms 3, and the transverse arm 4.

What we claim is—
